US00D838287S

(12) United States Design Patent (10) Patent No.: US D838,287 S
Low et al. (45) Date of Patent:  Jan. 15, 2019

(54) DISPLAY SCREEN OR PORTION THEREOF
WITH GRAPHICAL USER INTERFACE

(71) Applicant: GrowPath, Inc., Durham, NC (US)

(72) Inventors: Richard Christopher Low, Durham, NC (US); Tara Jean Williams, Republic, MI (US)

(73) Assignee: GrowPath, Inc., Durham, NC (US)

() Term: 15 Years

(21) Appl. No.: 29/627,827

(22) Filed: Nov. 30, 2017

(51) Loc (11) Cl. 14-04
(52) U.S. Cl.

(52) U.S. CL. USPC D14/486
(58) Field of Classification

(58) Field of Classification Search
LSCD G

USPC D14/485-495
GPO G-367-2/342-2/34287

CPC G06F 3/048-3/04
